DEVICES FOR TEACHING DIVING
Raymond Brosse, 67 Ave. du Marechal Foch, 95
Deuil-la-Barre, France
Filed Oct. 31, 1966, Ser. No. 590,965
10 Claims. (Cl. 272—1)

ABSTRACT OF THE DISCLOSURE

A device for teaching diving has a fixed frame and a movable board with a head portion and a foot portion to support a diver. The board is connected to the frame by two crossing rods each pivoted to the board and the frame for turning the board over as the rods move from an upright position to a horizontal position. The board is returned to the upright position after the diver slides from it.

The present invention relates to devices for teaching diving, in particular in a bathing pool.

The device according to my invention comprises, on the one hand, a movable supporting plate or board along which the diver is to take place, this board being connected to a fixed frame by a mechanism for shifting it from an upper nearly vertical position, which is the initial position for the diver, to an inclined lower position from which the diver is thrust into water and which corresponds to the position to be occupied by the diver just as it is entering water, and, on the other hand, means for returning, after the diver has been thrust into water, the board from its lower inclined position to its nearly vertical upper position.

Preferred embodiments of the present invention will be hereinafter described with reference to the appended drawing, given merely by way of example, and in which:

FIG. 1 shows, in vertical view, a device for teaching diving made according to a first embodiment of the invention;

FIG. 2 is a similar view of another embodiment of the invention.

The device according to the present invention essentially comprises, on the one hand, a movable board 1 against which the diver 2 is placed, this board 1 being connected to a fixed frame 3, secured to the edge of the bathing pool P through a mechanism capable of shifting it from a nearly vertical upper position for which the diver 2, placed along said board 1, is in the position he is to occupy before diving, to an inclined lower position which is the position from which the diver is to be thrust into water; and on the other hand, means for returning, after diver 2 has left board 1, said board from its inclined lower position to its nearly vertical upper position.

As shown by the drawing, the board 1 has a flat elongated surface provided at its lower end with a right angled rest or step 1a, upon which the diver's feet are resting. Preferably, as shown, the length of board 1 is lower than the average human height so that the head of diver 2 extends above the top of board 1.

In order to enable diver 2 to occupy a correct position with respect to board 1, the latter may be provided in its upper middle edge with a notch (not shown) opposite which the head of diver 2 must be located.

2

Concerning fixed frame 3, it comprises a vertical upright 4, the lower end of which is anchored in the edge of bathing pool P and the upper portion of which is provided with a platform 5 which can be reached by means of a ladder 6.

5 The operating mechanism is advantageously constituted, as shown by the drawing, by a system of rods 7-8 suitably articulated and adapted to work under the combined actions of the weight of diver 2 and of a weight 18.

This mechanism comprises, on the one hand, a first rod 7 hinged to board 1 about horizontal axis X—X and to fixed frame 3 about horizontal axis Y—Y, and on the other hand, a second rod 8, hinged to board 1 about a horizontal axis X₁—X₁ and to fixed frame 3 about a horizontal axis Y₁—Y₁, the respective positions of these four axes being such that rods 7 constitute the diagonals of the quadrilateral the apexes of which correspond to the projections of said axes on the plane of FIG. 1 or 2.

20 Counterweight 18 is connected to board 1 through a cable 15 having one end thereof secured to an arm 14 rigid with the first rod 7 and extending beyond pivot axis Y—Y, said cable passing over a pulley 17 freely rotatable about an axis fixed with respect to the upper part of vertical upright 14 and being secured at its other end to counterweight 18.

25 In FIG. 1, I have shown in solid lines the upper position of board 1 and, in dotted lines, two other positions thereof, to wit an intermediate position where board 1 is substantially horizontal and the lowest position of said board.

30 To control the pivoting of board 1 about axis X—X, vertical upright 4 carries a plate provided with an elongated hole, or guide slot 9, to vary the position of axis Y₁—Y₁.

35 According to a modification, not shown by the drawings, I might provide means for varying the length of the second rod 8, such means consisting, for instance, of a threaded rod having right and left screw threads.

40 The device further comprises means for locking board 1 in its upper position. In the embodiments illustrated by the drawings the locking device comprises a hook 10 carried by the first rod 7, a movable pawl pivoted to fixed frame 3 about a horizontal axis and provided with a return spring 12, and a starting member consisting of a pedal 13 mounted on platform 5 close to the edge of the rest 1a of board 1, so that the diver can operate this starting member 13 without having to modify substantially his position with respect to board 1.

45 According to a modification of the invention, not shown by the drawings, the starting member might be located close to the driver's hand. It might also be mounted in such manner as to be operated by someone other than the diver, said member being then either located on the fixed frame or telecontrolled by a person from a remote position so that this person can appreciate the driver's behaviour.

50 The returning means for board 1 are advantageously arranged in such manner as to store up the energy produced by the downward movement of board 1. Furthermore, shock absorbing means are provided for eliminating shocks at the end of the downward movement of board 1.

55 60 The return means comprise, for instance, a cable 19

secured at one end to arm 14 and passing over a pulley 16 provided at the lower end of upright 4, said cable having its other end secured to a rod 20 screwed in a plate 21 slidably mounted in a tube 24 carried by frame 3, with the interposition of a spring 22.

When board 1, under the action of the diver's weight and of weight 18, passes from its upper position to its lower position, it compresses spring 22.

In order to adjust the action of spring 22, rod 20 is screwed in a bolt 23 which connects it to movable plate 21.

It should be noted that I might also use an arrangement, not illustrated, wherein spring 22 would be mounted in upright 4.

In the embodiment of FIG. 2, the cable 39, secured to arm 14, passes over a pulley 38 carried by the lower end of upright 4 and is secured at its other end to a resilient strip 40, for instance of the "Sandow" type.

When board 1, under the action of diver 2 and of weight 18, passes from its upper to its lower position, it stretches resilient strip 40.

In the embodiment of FIG. 2, said strip 40 is mounted vertically in upright 4, the lower end of said strip being secured to cable 39 and its upper end being fixed to platform 5 through an adjustment device 41.

As for the shock absorbing device, it may advantageously consist, as shown by FIGS. 1 and 2, of a double action shock absorber 25, preferably adjustable, the fluid used in this shock absorber being air.

According to the embodiment illustrated by FIG. 1, this shock absorber 25 comprises a cylindrical body 26 located in the upper portion of upright 4 and a piston 27 rigid with a rod 28, the lower end of which is held in a sliding piece 29 cooperating with a slideway 30 carried by the lower portion of upright 4. Of course, the length of said slideway 30 is at least equal to the amplitude of displacement of piston 27 in shock absorber 25.

Sliding member 29 is operatively connected with board 1 through a rod 31 pivoted to sliding member 29 and slidable in a bore 32 provided in arm 14.

According to the embodiment of FIG. 2, the lower end of the rod 28 of piston 27 carries, slidably in a slideway 44, a pivot 42 journalled in a sleeve 43 slidable on arm 14, slideway 44 being of length at least equal to the stroke of piston 27 in shock absorber 25. The shock absorbing effect is obtained by providing, in the vicinity of both ends of the body 26 a shock absorber 25, two calibrated orifices, to wit, on the one hand, a calibrated orifice 33 located in the vicinity of the upper end of body 26 and producing the desired shock absorbing effect when board 1 passes from its upper position to its lower position, said calibrated orifice 33 being provided with an adjustable closing member 34; and on the other hand, a calibrated orifice 35 located close to the lower end of body 26 and producing a shock absorbing action during the shifting of board 1 from its lower position to its upper position.

Concerning closing member 34, it may be adjusted at the level of the shock absorber, in particular in order to take into account the weight of the diver. It may also be operated from a distance, in particular in order to adjust the downward speed of board 1.

In order to obtain a reinforced shock absorbing effect at the end of the stroke, the calibrated orifices 33 and 35 should advantageously be arranged in such manner that, calibrated orifice 33 is closed by piston 27 before board 1 has reached its lowest position, the shock absorbing effect being obtained through a leak of air (not shown) permitting a cross section of flow much smaller than that of calibrated orifice 33; and calibrated orifice 35 is closed by piston 27 before board 1 has reached its upper position, the shock absorbing effect being obtained through an air leak (not shown) giving a section of flow substantially smaller than that of calibrated orifice 35.

It should be pointed out that, as shown by FIG. 2, it is advantageous to provide, at the level of the pivot

axis Y-Y of the first rod 7, two packing members 45 and 46, made of a plastic material and intended to prevent any ingress of water, sand, pebbles and the like into tubular structure 4 forming frame 3.

5 I may also provide resilient abutments 47 at the places where shocks of a metallic piece against another metallic piece might occur, such resilient abutments 47 being for instance disposed, as shown by FIG. 2, at the level of platform 5 to prevent a possible shock of the first rod 7 against platform 5, and at the level of tubular upright 4 to absorb a possible shock of arm 14 against said element 4.

Such a device has the following advantages: autonomous operation without making use of an external source of energy; possibility of adjusting the inclination of board 1; possibility of adjustment in accordance with the diver's weight, by adjustment of the strength of the return spring and/or of the shock absorbing means; absence of shocks at the ends of the movement of the board, and no necessity of maintenance means.

In a general manner while I have, in the above description, disclosed what I deem to be a practical and efficient embodiment of the present invention, it should be well understood that I do not wish to be limited thereto as there might be changes made in the arrangement, disposition and form of the parts without departing from the principle of the present invention as comprehended within the scope of the appended claims.

What I claim is:

1. A device to teach diving which comprises, in combination;

a fixed frame,

a movable board having a head portion and a foot portion, to support a diver, deformable means for connecting said board to said frame between an upper position of said board where it is substantially vertical and a lower position thereof where it is claimed to let the diver slide head down therefrom,

said deformable means comprising two connecting rods, each pivotally connected at its ends to said movable board and to said fixed frame, respectively, and means for returning said board into the upper position after the diver has slid down therefrom.

2. A device according to claim 1 wherein said board includes a rest for the diver's feet, at the foot portion of said board.

3. A device according to claim 1 wherein said connecting rods include;

a first rod pivoted about two horizontal axes, a first one and a second one, respectively, on the one hand to an intermediate part of said board and on the other hand to the bottom part of said frame, and a second rod pivoted, about two horizontal axes, a first one and a second one, respectively, to a part of said board below it and nearer the head portion thereof than the first of said two first mentioned axes, and to the bottom part of said frame, said two rods crossing each other between their ends.

4. A device according to claim 3 further including; an arm rigid with said first rod and extending on the other side of said second pivot axis thereof, a pulley freely pivotable on said frame at the top portion thereof about an axis parallel to said horizontal axes,

a cable secured at one end thereof to said arm and passing on said pulley,

and a weight secured to the other end of said cable.

5. A device according to claim 3 wherein said frame includes a substantially horizontal slot and the second pivot axis of said second rod is adjustable in said slot.

6. A device according to claim 3 further including releasable means for locking said first rod with respect to said frame in the upper position of said board.

7. A device according to claim 3 further including energy storing means operatively connected with one of said rods for returning said board into upper position after the diver has slid therefrom.

8. A device according to claim 7 further comprising 5 shock absorbing means adapted to operate when said board is nearing one of its end positions.

9. A device according to claim 7 wherein said energy storing means include a spring.

10. A device according to claim 7 wherein said energy 10 storing means include a flexible strip.
